Primary Examiner — T Chase Nelson*Assistant Examiner* — Jonathan J. Han(74) *Attorney, Agent, or Firm* — Berg Hill Greenleaf Ruscitti LLP(57) **CLAIM**

The ornamental design for a LED key chain light, as shown and described.

DESCRIPTION

FIG. 1 is a perspective view of the LED key chain light showing our new design;

FIG. 2 is a left side elevation view thereof;

FIG. 3 is a right side elevation view thereof

FIG. 4 is a front elevation view thereof;

FIG. 5 is a rear elevation view thereof;

FIG. 6 is a top plan view thereof; and,

FIG. 7 is a bottom plan view thereof.

The broken lines in the figures show portions of the invention that form no part of the claimed design.

1 Claim, 4 Drawing Sheets(56)
